UNITED STATES PATENT OFFICE

PATRICK J. FITZGERALD, OF TORRINGTON, CONNECTICUT, ASSIGNOR TO THE FITZGERALD MANUFACTURING COMPANY, OF TORRINGTON, CONNECTICUT, A CORPORATION OF CONNECTICUT

DRIVING ATTACHMENT FOR MIXING BOWLS

Application filed July 28, 1931. Serial No. 553,629.

This invention relates to improvements in mixing bowls, and particularly concerns a driving device for connecting the beater mechanism and the bowl.

5 One of the features of the present invention is a separable driving device which is operated from the beater mechanism and itself operates to rotate the mixing bowl.

Another feature of the present invention 10 is a construction of the beater mechanism by which a power driven mechanism receives a bowl driving attachment which operates to rotate the bowl so that all parts of the contents of a bowl are operated upon by an 15 eccentrically mounted mixer.

Other features of the invention will appear in the course of the following description in conjunction with the drawings.

20 In these drawings is set forth an illustrative form of construction of the device, and—

25 Figure 1 is a plan view of the mixing bowl and driving attachment, with parts of the driving mechanism of the beater shown in section.

Figure 2 is a view in section on line 2—2a of Figure 1 of the bowl and driving attachment, and on line 2—2b of the beater mechanism, showing the assemblage of these 30 parts in their relative operating positions.

Figure 3 is a perspective view of the supporting bowl for the driving attachment.

Figure 4 is a perspective view of the housing plate for the beater mechanism.

35 Figure 5 is a fragmentary section substantially on line 5—5 of Figure 2.

In the drawings, a stand is illustrated 40 having a base 10 and a column 11 upon which is mounted the motor M for driving the beaters. The stand likewise has a socket 12 for receiving the pin 13 of the bowl B. The motor M is mounted with a vertical axis and has its shaft 14 extending downwardly 45 into a gear housing 15 having a bottom closing plate 16. Within this housing the shaft 14 carries a pinion 17 in mesh with a large gear 18 rotatably mounted on a sleeve 19 supported in the housing and having its 50 open end exposed below the plate 16.

A beater assembly comprising the U-

shaped wire 20 has the revolute beaters 21 thereon which are fixed at their upper ends to the gears 22, 23 which mesh with one another so that when the gear 22 is turned both beaters are driven in unison in the usual way. A gear guard 24 enshrouds the gears and prevents injury. Within the gear guard is a bushing 25 surrounding the fixed arm of the beater frame wire 20 and revolute thereon, and having its upper end adapted to enter into driving engagement with the inner wall of the sleeve 19 (Figure 2). A squared tube 26 is fixed to the upper end of this leg of the frame wire 20 and enters a square hole 27 in the housing 15, in which it 60 may be clamped by a thumb screw 28.

The upper end of the other leg of the frame wire 20 passes through a support 29 rigid with the guard 24 and has a projecting 70 stub 30 which is received in a hole 31 of the plate 16 and in a cavity 32 of the housing 15.

The plate 16 extends beyond the housing 15 to provide a pair of upwardly turned ears 35 which are located substantially in the same vertical plane and a horizontal flat 75 portion 36 terminating in an upwardly directed ear 37.

The beater attachment has a central bolt portion 40 having a stirrup 41 at its upper end provided with a pin 42. Surrounding this bolt is a sleeve 43 having a gear 44 fixed at its upper end and a driving wheel 45 fixed at its lower end, and being provided with a groove by which it may rest on the curled upper edge Ba of the bowl B. A spacing washer 46 permits the free rotation of the assembly 43, 44, 45, and is held in position by a nut 47 on the lower end of the bolt 40.

In operation, as the motor M revolves, the motor shaft 14 and pinion 17 are driven and therewith the large gear 18 which transmits its movement through the sleeve 19 to the bushing 25 of the right hand beater in Figure 2, and the latter in turn delivers its movement through gear 22 to gear 23 and thus drives the left hand beater.

The driving attachment assembly may be placed and moved as a unit. In placing it 100 in position, the pin 42 is located between the

ears 35, 37 and then the driving member 45 is seated on the edge of the bowl. The assembly is then held gravitationally in position and the gear 44 is in mesh with the gear 5 23, and as the latter gear revolves, it turns the gear 44 and hollow shaft 43, and thus also the driving member 45 operates frictionally to rotate the bowl.

10 The beater attachment may be quickly and easily removed by simply lifting it from position. It has few parts and is easily cleaned if material from the bowl is spat-tered thereon.

15 It is obvious that the invention is not limited to the form of construction but that such may be modified in many ways within the scope of the appended claims.

20 Having thus described the invention, what I claim as new and desire to secure by Letters Patent, is:—

25 1. A mixer including a revolvably supported bowl, a beating device comprising a fixed member having a horizontal plate, a beater supported by said member and a first gear rotated with said beater, spaced up-turned ears on said plate, a pivot member supported between said ears, a revolvble shaft mounted on said pivot member, a second gear on said shaft in mesh with said 30 first gear, and a driving member on said shaft resting on the edge of said bowl.

35 2. A mixer including a revolvably supported bowl, a beating device comprising a fixed member having a horizontal plate, a beater supported by said member and a first gear rotated with said beater, spaced up-turned ears on said plate, a pivot member gravitationally supported between said ears and including a spindle extension, a hollow 40 revolvble shaft on said spindle, a second gear on said shaft in mesh with said first gear, and a driving member on said shaft gravitationally resting on the attaching of said bowl, whereby said pivot member, shaft, 45 gear and driving member may be removed by lifting the parts from said ears and bowl.

50 3. The combination with a mixer includ-ing a frame, a beating device comprising plural beaters with driving means for one beater mounted on said frame and inter-meshing gears on said beaters, and a bowl revolvably mounted on said frame, of a driv-ing member resting on the edge of the bowl, and a supporting and driving connection be-55 tween one of said intermeshing gears and said driving member, said connection having a pivotal mounting on said frame whereby it may be moved about a horizontal axis to present said driving member into and out of 60 engagement with said bowl, and the mem-ber is held by gravity in contact with said bowl during operation.

65 4. The combination with a mixer includ-ing a frame, a beating device comprising a member fixed to said frame and a plurality

of beaters journaled in said member and in-termeshing gears on said beaters, and a bowl revolvably supported on said frame, of a driving member resting on the edge of said bowl, a shaft having a demountable journal bearing on said fixed member and connected to said driving member, and a gear on said shaft adapted to mesh with one of said in-termeshing gears, said journal bearing per-mitting said shaft to rock about a horizontal 70 axis so that the driving member may gravi-tationally engage the edge of the bowl and said shaft gear may mesh with said inter-meshing gear and whereby the driving mem-ber may be swung upwardly out of engage-80 ment with the bowl and thereby said shaft gear be moved out of mesh with said inter-meshing gear.

5. A mixer including a frame, a beating device comprising a member fixed to the frame and a beater journaled in said member, a bowl revolvably supported on the frame, a driving member gravitationally resting on the edge of the bowl, a support on said fixed member, a shaft connected to said driving member, releasable means for connecting the beater and shaft in driving relationship, a journal device in which said shaft may rotate and having means for gravi-tationally engaging said support for pivotal 90 movement about a horizontal axis, whereby the shaft, device and member may be re-moved by simple lifting from the bowl and support.

In testimony whereof I affix my signature. 100
PATRICK J. FITZGERALD.
